(57) **CLAIM**

The ornamental design for a coffee grinder with integrally stored brush, as shown and described.

DESCRIPTION

FIG. 1 is a top left perspective view of a coffee grinder with integrally stored brush according to a preferred embodiment design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is bottom plan view thereof.

The broken lines in the figures are for illustrative purposes only and form no part of the claimed design.
